APPARATUS FOR PRODUCING WAVES IN
FLUID MEDIA

Francis Weldon Crawford, Bartlesville, Okla., and
John S. Kirby-Smith, Oak Ridge, Tenn., assignors
to Phillips Petroleum Company, a corporation
of Delaware

Application May 3, 1948, Serial No. 24,808

2 Claims. (Cl. 177—386)

1

This invention relates to a method of productive wave motion in a fluid medium. In another aspect, it relates to apparatus for producing waves of supersonic frequencies in gas or liquid media.

Prior supersonic wave generators have ordinarily utilized a member vibrating at supersonic frequencies which was in direct contact with the medium through which the supersonic waves were to be transmitted. The amplitude of vibration of the member was very small and, accordingly, the intensity of the resulting supersonic waves was not as high as desired in certain applications.

In accordance with our invention, the vibrating member is utilized to modulate a stream of fluid as it is discharged from an orifice rather than to directly create the supersonic waves in the fluid medium through which they are propagated. In this way, the intensity of the waves can be considerably increased and, further, the intensity is readily controllable by varying the velocity with which the fluid passes through the orifice. This is accomplished, in accordance with the invention, by forming at least a portion of the orifice of magnetostrictive material and causing such magnetostrictive material to vibrate at supersonic frequencies to effect corresponding variations in the size of the orifice. As a result, wave motion is produced in the fluid discharged through the orifice which wave motion is of supersonic frequencies.

It is an object of the invention to provide an improved method of and apparatus for producing wave motion in a fluid medium.

It is an object of the invention to provide apparatus which is simple to construct, economical to operate, and reliable in operation.

Various other objects, features and advantages of the invention will become apparent from the following detailed description taken in conjunction with the appended drawings, in which

Figure 1 is a front elevational view of the apparatus with a portion of the coil broken away;

Figure 2 is a sectional view taken along the line 2—2 of Figure 1; and

Figure 3 is a vertical sectional view of a modification of the invention.

Referring now to the drawings in detail, and particularly to Figure 1, the wave generator comprises a reservoir 10 to which a fluid, such as air, may be fed under pressure by a conduit 11. The reservoir 10 is defined by a cylindrical structure 12 formed of a large number of stacked concentric annular rings 13. Each ring has a slot

formed therein and these slots are aligned so as to form a slot-like orifice 14 extending lengthwise of the cylindrical structure 12, the rings being secured together and sealed by a suitable binder so as to form a single unitary structure. In accordance with the invention the rings are formed from a suitable magnetostrictive material such as nickel and, when a varying magnetic field is impressed thereon, the length of the rings changes slightly due to the magnetostrictive effect thereby causing corresponding variations in the width of the slot 14. In this connection, it will be noted that the portions of each ring which are adjacent slot 14 are, in effect, the ends of a straight piece of magnetostrictive metal and variations in the length of the metal piece cause changes in the width of slot 14.

A magnetic field is impressed upon each of the rings 13 by a coil 15 which is wound longitudinally around the cylindrical structure 12 and has its ends connected to the terminals 16 of a suitable alternating current source of a predetermined frequency. End caps 17 and 18 are secured to the respective ends of the cylindrical structure 12 by a suitable sealing compound 12A, such as a thermoplastic resin, and end cap 18 is provided with an opening for receiving the conduit 11 through which fluid under pressure is admitted to the reservoir 10.

When coil 15 is energized by an alternating current of supersonic frequency, a magnetic field is established in the magnetostrictive structure 12 and the strength of this field varies at the same frequency as the current applied to the coil. This causes corresponding variations in the width of the orifice 14 which modulates the fluid discharged therethrough, thus producing wave motion in the discharged fluid at the supersonic frequency of the alternating current applied to terminals 16. This permits generation of supersonic waves of greater intensity than has heretofore been possible since the movement of the magnetostrictive member does not directly produce the supersonic pressure variations or waves but, rather, the movement of the magnetostrictive member merely controls the pressure which is originally produced by compression of the fluid inside the reservoir 10. During operation of the device, of course, there is relative movement between end caps 17, 18 and the cylindrical structure 12 but this movement is very small in magnitude and the resilient thermoplastic material 12A sealing the end caps can readily accommodate this small movement without allowing excessive leakage of fluid at the

joints between cylinder structure 12 and end caps 17 and 18.

The modified construction shown by Figure 3 includes a cylindrical casing 20 having end caps 21, 22 secured thereto in any suitable manner. This structure defines a reservoir 23 to which fluid under pressure is admitted through a conduit 24. End cap 22 is provided with a tapered orifice 25 with which cooperates a complementary tapered end portion 26 of a magnetostrictive rod 27. A support 28 is provided for the rod 27 and this support is secured in any suitable manner to the end cap 21 so that the rod is supported with the tapered portion 26 very closely spaced to the orifice 25.

A coil 29 is wound upon the magnetostrictive rod 27 and the leads of this coil are connected to binding posts 29a which are provided in end cap 21. The binding posts 29a are connected by leads 30 to the respective terminals 31 of a suitable source of alternating current.

The structure of Figure 3 operates in substantially the same manner as that shown by Figures 1 and 2. When an alternating current is supplied to the coil 29, the tapered end 26 of the rod moves back and forth relative to the orifice 25 thereby periodically increasing and decreasing the size of this orifice at a frequency determined by the frequency of the alternating current supplied to terminals 31. As a result, fluid discharged from orifice 25 is modulated and provides waves in the medium of the same frequency as the alternating current. That is to say, pressure variations or waves are set up in the surrounding medium by the periodic increase and decrease in the size of the orifice which are then propagated through the surrounding medium. The frequency of vibration of the rod 27 may be made very high, if desired, so that high intensity ultrasonic waves of very high frequency and short wave length will be produced.

Although the invention has been described in connection with a preferred embodiment thereof, it will be understood that this description is not intended to limit the invention, the scope of which is defined by the appended claims.

We claim:

1. Apparatus for producing wave motion in a gaseous medium at supersonic frequencies which comprises, in combination, a cylindrical struc-

ture formed from stacked slotted annular rings of magnetostrictive material, the slots therein being aligned to form a narrow orifice, means for sealing the ends of said cylindrical structure, means for continuously supplying gas under pressure thru an opening in the sealing means at one end into the interior of said structure, and a coil having its turns lying substantially in radially extending axial planes and wound longitudinally about said cylindrical structure, said coil, when energized by alternating current of supersonic frequencies, causing corresponding variations in the width of said slot whereby the gas discharged from said orifice is modulated at supersonic frequencies.

2. Apparatus for producing wave motion in a gaseous medium at supersonic frequencies which comprises, in combination, a cylindrical structure formed from stacked slotted annular rings of magnetostrictive material disposed in side by side arrangement, the slots therein being aligned to form a narrow orifice, means for sealing the ends of said cylindrical structure, means for continuously supplying gas under pressure to the interior of said structure, and a coil wound toroidally about the wall of said cylindrical structure, said coil, when energized by alternating current of supersonic frequencies, causing corresponding variations in the width of said slot whereby the gas discharged from said orifice is modulated at supersonic frequencies.
